DESIGN FOR A FASTENER PRONG RING

Paul E. Fenton, Thomaston, Conn., assignor to
Scovill Manufacturing Company, Waterbury,
Conn., a corporation of Connecticut

Application January 27, 1940, Serial No. 89,778

Term of patent 7 years

To all whom it may concern:

Be it known that I, Paul E. Fenton, a citizen
of the United States, residing at Thomaston,
county of Litchfield, State of Connecticut, have
invented a new, original, and ornamental Design
for Fastener Prong Rings, of which the following
is a specification, reference being had to
the accompanying drawing, forming part thereof.

Fig. 1 is a top view of a fastener prong ring
embodying my new design, and

Fig. 2 is a front elevation thereof.

I claim:

The ornamental design for a fastener prong
ring, substantially as shown.

PAUL E. FENTON.
